Specification for Design.

Patented Feb. 3, 1914.

Application filed September 29, 1913. Serial No. 792,528. Term of patent 3½ years.

To all whom it may concern:

Be it known that I, LELAND E. CARTER, a citizen of the United States, residing at San Diego, in the county of San Diego and State of California, have invented a new, original, and ornamental Design for Paper-Weights, Curios, or Similar Articles, of which the following is a specification.

Reference being had to the accompanying drawing forming a part thereof, Figure 1 is a front elevation of a paper weight, curio

or similar article showing my new design. Fig. 2 is a side elevation of the same.

I claim—

The ornamental design for a paper weight, curio, or similar article, as shown.

In testimony whereof I affix my signature in presence of two witnesses.

LELAND E. CARTER.
